UNITED STATES PATENT OFFICE.

WILLIAM E. WINE, OF TOLEDO, OHIO.

RAILWAY CAR.

Application filed June 23, 1921. Serial No. 479,722.

To all whom it may concern:

Be it known that I, WILLIAM E. WINE, a citizen of the United States, residing at Toledo, in the county of Lucas and State of Ohio, have invented certain new and useful Improvements in Railway Cars, of which the following is a specification.

This invention relates to a device for forcing the doors of railway cars shut and for holding the same in closed positions. Among the objects thereof is to provide a simple device whereby the doors may be partly closed by hand, one at a time, and thereafter a wrench or other tool may be made use of to force the door into a tightly closed position. Another object is to provide means for preventing the accidental release of the doors and in general to provide improvements in devices of this character whereby the same may be economically constructed, and whereby the operations of releasing and closing the doors will be simplified and the effectiveness of the devices and the doors themselves increased.

With such objects in view, the invention consists of the formation, combination and arrangement of parts as will be herein described and particularly claimed.

In the accompanying drawings, Figure 1 is a fragmentary side elevational view of a portion of a car body having a drop door applied in the floor thereof and with a preferred form of the mechanism of the present invention shown as applied to the car and the door. Figure 2 is a transverse vertical section through the door structure, the same being taken approximately on the line 2—2 of Figure 1. Figure 3 is a horizontal section through the door securing device taken approximately on the line 3—3 of Figure 1. Figure 4 is a section taken in a vertical plane approximately coincident with the irregular line 4—4 of Figure 3 and showing a portion of the door and door mechanism when the door is not quite in closed position. Figure 5 is an end elevational view of the locking block or cam, detached from the remainder of the device.

Referring now to these drawings, the side of the car is denoted by the numeral 1, there being a bottom flange angle 2 supplied to the car side, the outstanding leg of the same being turned inwardly toward the center of the car to clear the door mechanism. A

door 3 is hinged to the car body by means of co-operating body and door hinge members 5 and 6, respectively, with pintles as at 7. The door plate 8 may extend beneath the inwardly turned horizontal leg of the angle 2 in order to provide a sufficient seal 60 against loss of material. The outer edge of the door, however, does not extend quite to the outer face of the car side 1 in order to avoid interference with portions of the door-retaining device. Extending across the door and beneath the door plate 3 is a stiffening angle 9, the same extending beyond the outer edge of the door plate 8 and somewhat outside of or beyond the side of the car. Secured to this reinforcing angle 70 9 is a two-part bracket, composed of the members 10 and 11 which are arranged in spaced relationship with each other, thereby providing an interval or opening between the portions 10 and 11 constituting this 75 bracket. The angle 9 is arranged somewhat back from the free edge 12 of the door, and the bracket members 10 and 11 extend outward from the angle toward, and may extend slightly past, the free edge 12 of the 80 door. The bracket members 10 and 11 are riveted to both legs of the angle 9 and accordingly serve to stiffen the angle, and all of the parts are thus securely tied together. 85

Rigidly secured to the car side by means of the rivets 13 is a bracket 14, which depends from the car side and has located at some distance beneath the line of the face of the door a hook member 15. The major portion of this bracket is located outside the 90 line of swing of the door and near the free edge of the same, but the hook portion 15 thereof overlies the line of swing of the door plate 8. This bracket being disposed upon the outer face of the side of the car, it lies 95 to one side of the door plate 8. It also entirely clears the line of swing of the angle iron 9. The bracket members 10 and 11, however, are arranged to over-reach the portion 15 of this bracket, but they are so disposed along the angle 9 that the interval therebetween will accommodate the hook portion 15 of the bracket 14, or, in other words, will permit the door to swing either 100 upward or downward past the projection 15 105 by having this portion arranged to register with the opening between the two-part

Movably arranged in the space between the members 10 and 11 and supported thereupon, as by pivoting at 16, is a cam or locking block 17. This cam block is pivoted upon the bracket members 10 and 11 immediately over the hook 15; but the cam block is also provided with a passage way 18 therethrough to accommodate the width of the hook 15, it being understood that the bracket members 10 and 11 are spaced far enough apart to accommodate the full width of the cam 17. When the cam 17 is turned straight downward it bears upon the top surface of the hook 15; but when it is swung as to the right in Figure 1 it allows the door to drop by permitting the hook 15 to pass through the opening 18 thereof. A cam lock 19 is also pivoted upon the bracket members 10 and 11 to retain the cam 17 in proper position against accidental movement. The members 10 and 11 are made separate instead of integral in order to assemble the cam 17 and cam lock 19 therebetween.

It is the intention that the doors shall be lifted up by hand, but is sometimes difficult to raise such doors by hand the full amount needed, due to the fact that foreign material or deformation of parts may cause the doors to bind before being fully closed. When a door is to be raised, the cam 17 will be swung around into the position shown in Figure 4. The door will now be lifted up until it is substantially in the position shown in Figure 4 with respect to the bracket 14.

The cam lock will then be moved into the position shown for it in full lines in Figure 4, which will permit the cam 17 to rotate until it strikes the point of the hook 15. It will be noted that with the cam lock in the dotted position it will hold the cam in such position as to permit the passage through the space 18 of the hook. By now raising the door slightly more the the corner 20 of the cam will rise above and drop in over top of the hook 15, and the door will thereby be temporarily supported, but it will not be in fully closed position. It will be noted that the outer end of the pintle portion of the cam 17 is made with a square end 21 so that a wrench may be applied thereto and the cam 17 forcibly rotated. The bottom surface of this cam being made eccentric with respect to the axis of rotation about the pivot 16, it will be seen that as the cam is rotated to bring it into the position shown in Figure 1, the door will be forced upward and fully closed into the position desired.

The invention as just described provides a simple, positive and efficient means for forcibly closing and for holding shut the doors of railway cars or the like, and having but few operating parts it will be appreciated that the same will not be liable to become inoperative as is frequently the case where more elaborate mechanisms are used.

Having thus described an embodiment of the invention, what is claimed is:

1. In combination with a railway car, a hinged door arranged in the floor of the car, with its outer edge lying slightly inside of the line of the car side, a reinforcing member affixed to the door and extending slightly outside of the line of the car side, a hook-shaped bracket rigidly secured to the outer face of the car side and depending below the lower edge of the same and below the line of the said door, and movable door-locking means carried upon the said reinforcing member on line with and co-operable with the said hook-shaped bracket, the same being arranged, when in one position, to swing with the door freely past the said rigid bracket, and when in another position to engage the said rigid bracket to prevent dropping of the door.

2. In combination with a railway car, a hinged door, a bracket carried by the door near one edge of the same, a movable locking member operable upon the bracket, the same having an opening in one of its sides, a door-retaining member attached to the car adjacent the edge of the door, the said door-locking member and door-retaining member being so associated that in one position of the locking member the retaining member will be movable through the said opening therein and in another position such movement therethrough will be prevented.

3. In combination with a railway car, a hook-shaped bracket affixed to the car body, a door pivoted upon the car with its free edge adjacent the said bracket, a bracket carried by the door, a hook-engaging member rotatably mounted upon the door bracket and arranged to seat upon the hook portion of the first mentioned bracket, the said rotatable member being so formed as to first engage the said hook when the door is partly closed and upon rotation thereof to force the door into fully closed position.

4. In combination with a railway car, a hook-shaped bracket affixed to the car body with the hook disposed beneath the line of the car floor, a door hinged in the car floor with the free edge thereof adjacent the said hook, a two-part bracket affixed to the free edge of the door near to and overreaching the said hook, there being an opening between the parts of the door bracket for the accommodation of the said hook, and hook-engaging means movably associated with the said door bracket.

5. In combination with a railway car, a hook-shaped bracket affixed to the car body with the hook disposed beneath the line of the car floor, a door hinged in the car floor with the free edge thereof adjacent the said hook, a bracket affixed to the free edge of the door near to and overreaching the said hook, there being an opening in the door

bracket for the accommodation of the said hook, and a movable member associated with the said door bracket, the same being so arranged that in one position thereof the door may have unrestricted movement with respect to the said hook, and in another position such relative movement will be prevented.

6. In combination with a railway car, a hook-shaped bracket affixed to the car body with the hook disposed beneath the line of the car floor, a door hinged in the car floor with the free edge thereof adjacent the said

hook, a bracket affixed to the free edge of the door near to and overreaching the said hook, there being an opening in the door bracket for the accommodation of the said hook, and a movable member associated with the said door bracket, the same being so arranged that in one position thereof the door will be held partly closed and that movement of the said member into another position will forcibly close the door.

In testimony whereof I affix my signature.

WILLIAM E. WINE.
